UNITED STATES PATENT OFFICE.

EDGAR M. BOUTON, OF EAST PITTSBURGH, PENNSYLVANIA, ASSIGNOR TO WESTINGHOUSE ELECTRIC & MANUFACTURING COMPANY, A CORPORATION OF PENNSYLVANIA.

MOTOR-CONTROL SYSTEM.

Application filed July 27, 1922. Serial No. 577,828.

My invention relates to systems of control and it has particular relation to systems that are adapted for the control of two-speed alternating-current motors for elevators, 5 hoists and the like.

One object of my invention is to provide a system of speed control for an alternating-current motor which shall be simple and efficient in operation.

10 Other objects of my invention will be evident from the following specification and the appended claims.

I propose to employ an alternating current motor in connection with my control system, 15 having two speeds corresponding to windings of different numbers of poles, and preferably of the slip-ring or wound-rotor type. The secondary windings are suitably connected to five slip rings, to which are also connected 20 two sets of auxiliary resistors. The resistors are star-connected and have sections thereof common to the circuits of both the high and the low-speed motor windings. Separate accelerating switches are employed for controlling 25 the resistors, but a single accelerating relay is utilized for controlling the acceleration and deceleration of the motor.

My invention will be more clearly understood by reference to the accompanying 30 drawing, in which the single figure is a dia-grammatic representation of circuits and apparatus embodying my invention.

In the drawing, a single motor is shown as provided with a low-speed primary winding 35 1, a low-speed secondary winding 2, a high-speed primary winding 3 and a high-speed secondary winding 4, all of the windings being illustrated as star-connected. The primary windings are respectively connected 40 through pole-changing switches 5 and 6 to supply conductors 7, 8 and 9. For reversing service, of course, the supply conductors are to be connected to the line conductors through reversing switches of any well-known type. 45 For simplicity, I have not shown such reversing means.

The motor secondary windings may have 50 unlike characteristics, that is, different normal values of voltage and current during operation. The low-speed secondary winding 2 is connected in star relation to accelerating resistors 11, 12 and 13. The high-speed secondary winding 4 is connected in star relation to the secondary resistors 14, 15 and 16.

It will be noted that the resistor section 13 55 is common to the circuits of both the high and the low-speed windings.

I employ a single accelerating switch 17 for the low-speed windings 2 and a plurality of accelerating switches 18, 19 and 20 for the 60 high-speed winding 4. The several accelerating switches are controlled by means of a multiple-finger current-limit relay 21. This relay constitutes the subject-matter of United States Patent No. 1,392,056, dated 65 Sept. 27, 1921, and assigned to the Westinghouse Electric & Mfg. Company. The construction of this relay forms no part of my invention, and is, therefore, illustrated 70 in diagrammatic form.

Assuming the various switches to occupy their inoperative or illustrated positions, the motor may be started by closing the high-speed switch 6, thereby immediately energizing primary winding 3 and secondary winding 4 through supply conductors 7, 8 and 9. A coil 22 of the relay 21 is connected through switch 6 to conductors 7 and 9. A calibrating coil 23, also constituting a part of the relay 21, is connected through a control resistor 24 80 across the resistor sections 13 and 16. Coil 23 is, therefore, energized in accordance with the current traversing the resistor sections 13 and 16 to prevent the immediate closure of the relay contact members 25, 26 and 27, 85 which are arranged to successively engage contact members 28, 29 and 30, respectively, in a manner fully disclosed in the above-mentioned patent.

When coil 22 is energized, it releases contact members 25, 26 and 27, which are then restrained only by the action of the calibrating coil 23. As the motor accelerates, variations occur in the potential across the resistor sections 13 and 16, permitting the release 90 of contact members 25, 26 and 27, which successively engage contact members 28, 29 and 30 to complete circuits for the operating coils of accelerating switches 18, 19 and 20. The acceleration of the motor is thus controlled 95 in a well-known manner in accordance with the drop in potential across the accelerating resistors 13 and 16, as fully disclosed in the above-mentioned patent.

When the motor has attained full speed 100 and it is thereafter desired to reduce the speed, this result may be accomplished by opening the switch 6 and closing the switch

5, which action de-energizes the high-speed motor windings 3 and 4 and energizes the low-speed windings 1 and 2. The accelerating relay 21 is promptly reset upon interruption of the circuit of coil 22, in turn causing the reinsertion of the accelerating resistors in the high-speed secondary circuit.

The closure of switch 5 energizes the low-speed windings 1 and 2; and the motor, 10 which has been running at a speed considerably in excess of the synchronous speed corresponding to the low-speed windings, is now subjected to a dynamic-braking action, as will be understood.

15 During the initial braking period, the resistor sections 11, 12 and 13 are in circuit with the secondary winding 2, being chosen of suitable ohmic value to limit the current and counter-torque of the motor, until the motor 20 speed has been materially reduced, after which the resistor sections 11, 12 and 13 are excluded from circuit by the action of the relay 21, the calibrating coil 23 being subject to the voltage-drop across the resistor section 25 13. The resistor section 16 is not included in the operating circuit of the low-speed motor winding 2 and this resistor section, therefore, carries only a low value of current, which is the value of current traversing the coil 23.

30 During the period of deceleration, the relay contact members 25, 26 and 27 are controlled in accordance with the drop in potential across the resistor section 13. The operating coil of switch 17 should be connected 35 to whichever one of these contact members provides the most suitable time interval for cutting out the low-speed secondary resistors, it being here shown as connected to the middle contact member 26 for excluding resistor sections 11, 12 and 13 from the motor circuit.

40 The motor now operates substantially at its lower synchronous speed, the speed varying, of course, in accordance with load conditions.

45 In elevator service, it will be understood that, at times, the motor is required to elevate heavy loads and that, at other times, the motor is driven or "overhauled" by the load. It is especially necessary, under these load conditions, to prevent a too sudden change in the operating speed of the motor, for which purpose I employ the resistor sections and the current-limit relay, in the manner described.

50 By the illustrated interconnection of the 55 main secondary windings and resistors, I am able to employ a single relay for controlling both the acceleration and deceleration of the motor, thereby greatly lessening the amount of control apparatus that is required to accomplish the desired results. It is manifest that, when desired, the motor may be started by the low-speed winding prior to its operation at high speed. I have described the usual method of starting, that is, by the high-speed windings, as I desire more particularly

to bring out the method employed in decelerating from high speed, which is perhaps the most difficult problem that is present in the control of motors in elevator service.

I claim as my invention:

1. The combination with an alternating-current motor having windings corresponding to different speeds and separate accelerating switches for each speed winding, of a single accelerating relay for controlling said switches. 70

2. The combination with an alternating-current motor having a low and a high-speed winding and separate accelerating switches for each speed winding, of an accelerating relay having a single calibrating coil for rendering said switches effective to gradually accelerate the motor. 80

3. The combination with an alternating-current motor having separate low and high-speed windings, of an accelerating resistor, means for connecting a portion of said resistor in circuit with either winding and another portion of the resistor in circuit with only one of said windings, and an accelerating coil in shunt relation to said resistor. 85

4. The combination with an alternating-current motor having low and high-speed windings and a resistor connected to a junction-point thereof, a portion only of said resistor being energized by the low speed winding, of an accelerating relay having a coil responsive to the drop in potential across the entire resistor for controlling the operation of the motor with either speed winding in circuit. 95

5. The combination with an alternating-current motor having low and high-speed windings and a resistor connected to a junction-point thereof, of an accelerating relay responsive to predetermined changes in the voltage across the resistor for controlling the effect of said speed windings, said relay controlling separate high and low-speed contact members. 105

6. In combination with an alternating-current motor having high and low-speed windings, circuits for said windings including predetermined values of resistance, means for varying the resistance of said circuit for controlling the rate of change of speed of said motor between zero speed and substantially synchronous speed of said high-speed winding comprising a relay having a coil connected in both the high and low-speed windings for energization by voltage in said windings, a second coil connected for constant voltage opposing the effect of said first named coil, and means operable by variations in the combined effects of said coils for varying the resistance of said circuits, as said motor speed increases and decreases with either of said windings in use. 110

In testimony whereof, I have hereunto subscribed my name this 15th day of July, 1922.

EDGAR M. BOUTON.
